UNITED STATES PATENT OFFICE.

JOHN SOŚNIERZ, OF MCKEES ROCKS, PENNSYLVANIA.

WRENCH.

1,040,802.

Specification of Letters Patent.

Patented Oct. 8, 1912.

Application filed March 8, 1912. Serial No. 682,366.

To all whom it may concern:

Be it known that I, JOHN SOŚNIERZ, a subject of the Emperor of Austria-Hungary, residing at McKees Rocks, in the county of Allegheny and State of Pennsylvania, have invented certain new and useful Improvements in Wrenches, of which the following is a specification, reference being had therein to the accompanying drawing.

5 This invention relates to wrenches, and the primary object of my invention is to provide a quick acting wrench consisting of comparatively few parts that are inexpensive to manufacture, easy to assemble and 15 highly efficient for the purposes for which they are intended.

10 A further object of this invention is to provide a nut wrench with a tilttable and adjustable jaw that can be easily and 20 quickly shifted into engagement with a nut whereby the wrench can be safely used without any danger of the same slipping.

25 With the above and other objects in view, the invention resides in the novel construction, combination and arrangement of parts to be hereinafter specifically described and then claimed.

30 Reference will now be had to the drawing, wherein:—

35 Figure 1 is a side elevation of a wrench in accordance with this invention, Fig. 2 is a similar view partly broken away and partly in section, and Fig. 3 is a similar view showing the adjustable jaw tilted in dotted lines.

40 A wrench in accordance with this invention comprises a shank 1 rectangular in cross section and having the front side thereof provided with ratchet teeth 2, said teeth being arranged intermediate the ends of the shank.

45 The inner end of the shank constitutes a handle by which the wrench is held, and the outer end of the shank is provided with a fixed jaw 3 that extends from the front side of the shank and presents a flat gripping surface 4.

50 Slidably and tiltably mounted upon the shank 1 is an adjustable jaw body 5 that has a strap 6 embracing the shank 1, said strap having the inner end thereof provided with a thumb piece 7, whereby the jaw can be easily manipulated. The jaw body 5 has the inner end thereof extended beyond the strap 6 and provided with teeth 8 meshing with the teeth 2 of the shank 1. With the 55 teeth 8 in engagement with the shank 1, the

body of the jaw 5 is spaced from the front side of the shank 1, as at 9 and the strap 6 is held in engagement with the rear side of the shank 1 by a spring pressed pin 10 slidably mounted in an angularly disposed recess 11 provided therefor in the jaw 12 of the body 5. The end of the pin 10 being disposed at an angle to the front side of the shank 1 frictionally engages said shank, retaining the teeth 8 in engagement with the teeth 2 and preventing the jaw body 5 from slipping while in use.

60 The teeth 8 of the jaw body 5 will recede over the teeth 2 of the shank 1 when the jaw body 5 is shifted toward the fixed jaw 4, and when it is desired to move the jaw body 5 away from the jaw 4, the thumb piece 7 is 70 pressed upon to tilt the jaw body 5. When pressing the thumb piece 7, the pin 10 recedes into the recess 11 and with the inner 75 end of the strap 6 as a fulcrum point, the teeth 8 of the jaw body 5 are shifted out of engagement with the shank 1, as shown by dotted lines in Fig. 3.

80 When the jaw body 5 is open to that extent that the teeth 8 pass out of engagement with the teeth 2, the spring pressed pin of the jaw 12 then engages the teeth 2, as shown in Fig. 3 and preventing the jaw body 5 from slipping relatively to the shank. 85

85 It is apparent from the foregoing that the wrench consists of comparatively few parts that are not liable to injury by ordinary use and that are inexpensive to manufacture.

90 What I claim is:—

95 A wrench comprising a shank having the front edge thereof toothed and its outer end formed with a fixed jaw, an adjustable and tilttable jaw body normally spaced from said toothed edge, a strap having its sides integral with the forward portion of said jaw body and constituting means for connecting the jaw body to the shank, the sides of said strap normally projecting from the toothed edge of the shank, a jaw projecting from 100 said body, an extension integral with and projecting inwardly from said jaw body and having an inturned free end formed with an inner face of greater length than the width of the extension, said inner face provided 105 with teeth capable of engaging with the teeth of the shank, the inturned free end of said extension positioned in a plane parallel with the plane of the inner face of the jaw body, an angularly disposed cylindrical 110

member mounted in the forward part of said
jaw body and capable of engaging the shank
for retaining the teeth of the extension in
engagement with the front side of the shank,
5 said cylindrical member further constituting
means for engaging the teeth of the shank
to prevent shifting in one direction of the
jaw body, and a coiled spring carried by the

jaw body and abutting against one end of
said pin.

In testimony whereof I affix my signature
in the presence of two witnesses.

JOHN SOŚNIERZ.
